UNITED STATES PATENT OFFICE.

JAMES C. WALKER, OF WACO, TEXAS.

ROTARY ENGINE.

SPECIFICATION forming part of Letters Patent No. 611,585, dated September 27, 1898.

Application filed December 27, 1897. Serial No. 663,783. (No model.)

To all whom it may concern:

Be it known that I, JAMES C. WALKER, of Waco, in the county of McLennan and State of Texas, have invented a new and Improved 5 Rotary Engine, of which the following is a specification.

This invention relates generally to improvements in that class of rotary engines having concentric pistons; and it refers more particularly to improvements on the engine mechanism disclosed in my Patent No. 515,631, dated February 27, 1894.

Primarily this invention seeks to provide an engine embodying the combination of parts 15 shown in my other patent with certain improved cut-off devices and mechanism adapted to impart a reverse movement to the piston and drive-shaft.

This invention also seeks to provide certain 20 additional features to the cylinder and modifications in the construction thereof which will render the said patented engine of a more practical and stable construction, in which the cut-off devices are so arranged as to obtain 25 the full effect of the live and expansible steam forces, whereby a maximum impact energy on the piston is obtainable in a substantial uninterrupted manner and without the undue jarring on the several parts constituting 30 the engine, such as is usually encountered in the practical use of engines of this class.

With various other minor objects in view, all of which will hereinafter be fully set out, the invention consists in a rotary engine embodying the peculiar combination, construction, and novel arrangement of parts, such as will be first described in detail, and then be specifically pointed out in the appended claims, reference being had to the accompanying drawings, in which—

Figure 1 is an elevation of my improved rotary engine, one pair of cylinders being shown in side elevation and the other pair in vertical section. Fig. 2 is a vertical section of the 45 same, taken on the line 2 2 of Fig. 1, looking in the direction of the arrow. Fig. 3 is a similar view taken on the line 3 3 of Fig. 1 in the direction of the arrow. Fig. 4 is a diagrammatic face view of one of the cylinders 50 and valve-shifting devices hereinafter specifically referred to. Fig. 5 is an enlarged vertical section taken on the line 5 5 of Fig.

3. Figs. 6 and 7 are detail views of the inlet and exhaust ports, the shifting valves, and a portion of the operating devices therefor. 55 Fig. 8 is a transverse section on the line 8 8 of Fig. 5.

In the practical construction of my present invention the cylinders, drive-shafts, and the abutments are arranged substantially the 60 same as in my patent referred to, with the exception that the inner halves of the two sets of cylinders are cast or otherwise formed integral, leaving the solid metal around the drive-shaft, whereby the structure of the cylinders is more stable and more solid bearings 65 for the drive-shaft provided.

The four cylinders B B' B² B³ are arranged in pairs, as before, but the two pairs are separated sufficiently to provide for the convenient application of the valve-operated devices 70 and the shaft-operated cam mechanism therebetween.

The outer and inner halves of the two pairs of cylinders are firmly bolted to the solid portion of the cylinders and are held steam-tight by the outer packing-rings P, and the additional packing-boxes P' P'', disposed over the drive-shaft A⁵, and the rings P² P³, fixedly secured to the drive-shaft, steam-tight against 80 the cylinder, as clearly shown in Fig. 1.

To provide for a convenient discharge of the condensations within the cylinders, such cylinders are each formed with a collecting-well having outlet-pipes P⁴ P⁵ P⁶ P⁷, which 85 empty into a valve outlet-pipe P⁸.

As in my other patent referred to, the valve-operating devices and the pistons in the present structure are so arranged as to provide for a live-steam impact on the shaft at each 90 quarter-revolution thereof to gain the maximum speed and power and maintain the rotation of the shaft at all times practically under a live-steam-impact force, and also obtain the full effect of the expansive force of the steam- 95 heat in each cylinder.

In my patented construction of engine the abutments in each pair of cylinders are arranged at diametrically opposite points, the abutment of one pair being intermediate the 100 abutment of the other pair to obtain the results desired. In the present structure the abutments are all arranged at the top of the cylinders in alinement, but the pistons are

arranged on quarters and the valve and abutment-slide operating devices so disposed as to effect a successive operation alternately on the slides of the cylinders, as will hereinafter be made clear.

By referring now more particularly to Figs. 1 and 2 it will be observed the abutment valves $O^{10} K^{18} M M^6$ are held to slide in casements O^8, K^{17}, M' , and M^4 , the abutment slide-valves having rods O^7, K^{16}, M^3 , and M^5 operating through steam-tight guide-apertures. To the upper ends of these rods are secured rock-levers S, K^4, H^{11} , and L^7 , to which are fixedly joined pendent levers O^5, K^{15}, H^9 , and L^8 , the lower ends of which are connected to the rock-shafts O^{13}, K^{12}, K' , and K . The rock-levers S, K^{14}, H^{11} , and L^7 are also provided with rods O^6, K^{13}, H^{10} , and L^4 , which connect, respectively, with the rock-shafts O^{12}, K^{20}, K^1 , and K^3 . The rock-shafts O^{12}, O^{13}, K^4 , and K' are in the nature of tubular sections, in which the other rock-shafts are held to rotate, all of such shafts being journaled in suitable bearing-supports 10, projected up from the cylinder-casing and having suitable collars or cuff members, in which such shafts revolve in part. To the tubular shaft K' is connected a crank-lever H^{13} , which has a hinged connection with a downwardly and inwardly extending pendent pitman-rod H^7 , which is pivotally connected to the upper end of the sliding shaft H^6 , (see Fig. 2,) the lower end of which is connected with the curved member of the vibrating lever H , which is operated by the upper side of cam A, secured to the cam-disk D, the construction of which will be presently more fully disclosed. To the upper end of lever H^6 is also fixedly connected a rod H^8 , which forms a mate to the rod H^7 and is projected in an opposite direction, its upper end being pivotally connected with the crank-arm H^{12} , which is connected to and operates the tubular rock-shaft K^4 .

By referring now more particularly to Fig. 2 it will be seen that rock-shafts K and K^3 have inwardly-projecting cranks L^5 and L^6 , to which the lever-rods L^2 and L^1 are respectively pivotally connected, the lower ends of which are fixedly connected to the vertically-sliding shaft L, the lower end of which is fixedly connected to the curved member of the vibrating lever-arm H' , operated by the cam A' of the disk D. The levers H and H' , referred to, are journaled on suitable cross-rods 20, as shown in Fig. 1. Each cylinder is provided with a steam-chest formed of three compartments 20, 20', and 20'', as most clearly shown in Fig. 6. In the compartment 20 is fitted a valve H^{23} , which is operated by hand-operated rock-shafts $R R'$, (see Figs. 1 and 4,) which shafts are connected by levers R^3 and R^4 to cause them to move in the same direction. When the shafts R and R' are rocked in the direction indicated by the arrow 12 in Fig. 4, the connecting-levers H^{28}, H^{29}, H^{32} , and H^{33} , joined at one end with the valve H^{23} and at the other end to the crank members H^{27} ,

H^{33}, H^{30} , and H^{31} , projected up from the rock-shafts $R R'$, will cause such valve H^{23} to slide in the direction indicated by the full-line arrow over the inlet H^{19} and open the port H^{20} . When the shafts $R R'$ are moved to slide the valve H^{23} , as stated, the cover-plates H^{36} and H^{35} , which are connected with the valve H^{23} by a suitable slide-frame, are moved to close the exhaust H^{21} and open the exhaust H^{22} . At this time a valve-plate H^{17} is held over the feed-port h^{19} to inlet by the action of a lever H^4 . (See Fig. 2.) This lever H^4 connects with the valve-plate H^{17} by a link H^{16} , bell-crank H^{15} , and pitman H^{14} , joined substantially as shown, such lever H^4 being suitably fulcrumed at 4 to the fixed support.

H^{18} indicates a valve-plate which operates over the feed-port h^{20} to inlet H^{20} , and which in turn is operated by the lever H^5 , constructed and manipulated like lever H^4 . It should be stated that the levers H^4 and H^5 are operated alternately—i. e., as lever H^4 is set in an operative condition the lever H^5 will be out of gear. (See full lines in Fig. 2.) When the lever H^5 is set for operation, live steam will enter through port H^{20} at one side of the abutment and escape through the exhaust H^{22} at the opposite side of the abutment, it being understood that during this operation the inlet H^{19} is held permanently closed by the valve H^{23} , the lever H^4 at this time being held out of gear with the disk-operating devices presently referred to. Thus it will be readily understood that when taking steam through the inlet H^{20} the piston is driven from right to left, (see arrow x,) and when the lever devices H^4 are set for operation the motion of the engine is reversed, it being also understood that to effect such reverse motion the shafts R and R' are turned to a reverse position to bring the valve H^{23} to close H^{20} and open the port H^{19} , the lever H^5 during the reverse movement being thrown out of gear and the lever H^4 into an operative position, leaving the valve H^{17} free to be operated by the said lever H^4 .

In the present structure two operating-disks are provided secured on the drive-shaft between the central pair of cylinders, one of such disks being provided for each set of cylinders. In Figs. 2 and 3 the two sides of the same disk are represented, the side shown in Fig. 2 being the one next the center of the machine and the side shown in Fig. 3 being the one next the cylinder B'. The disk D is fixedly secured to the drive-shaft and has at diametrically opposite points apertures d , in which block-weights E and E' are held to slide upon guide-rods d' , which weights are normally held to their inward position by the springs E⁶ and E⁷, as shown. The disk D is also provided with sockets or guides disposed at right angles to the aperture d , in which are held to slide weights E⁴ and E⁵, the weight E⁴ being on one side and the weight E⁵ being on the reverse side and opposite the weight E⁴. Weights E and E' are common to both

sides of the disk. The weights E^4 and E^5 are connected by means of suitable pivotal arms E^8 and F^9 with the weights E and E' .

5 F^F and F^2 F^3 designate cut-off pieces pivotally secured upon opposite sides of the disk D , which are adapted to engage with the reverse-levers H^4 and H^5 and similarly-arranged levers H^3 and H^2 , the purpose of which will presently appear, the disk F being adapted 10 to cut off steam when the piston is in direct motion from left to right, the cut-off F' serving the same purpose when the piston is on the reverse motion for the adjacent cylinder B' , while the disks F^2 and F^3 serve the same 15 purpose for cutting off the steam in the forward and reverse motion of the piston in cylinder B . All of the cut-off devices are constructed and connected with the disk in a like manner. They are pivoted at the end 20 next the drive-shaft and extend outward, preferably in diamond shape, as shown, their ends projecting beyond the ends of the inner perimeter of the disk D , so as to come in contact with the several levers operating the inlet- 25 valves and force them out toward the periphery of the disk, as clearly shown in Fig. 2, whereby to engage such levers H^4 , H^3 , H^2 , and H^5 as may be set in an operative position and lift them to cause a corresponding closing 30 movement on the steam-chest valves connected therewith. The levers H^3 and H^2 serve the same purpose for the cylinder B that the reverse H^4 and H^5 do for the cylinder B' .

Assuming the parts to be in the position 35 shown in Fig. 2 and the disk to be turned in the direction indicated by the dotted arrow and the lever H^5 up in a position out of the path of movement of the cut-off F' , the lower edge of the cam A (shown in full lines) will 40 come in contact with the lever H^5 and force it down to the position shown in dotted lines. This operation, through the several connecting-levers joined with the lever H^4 , opens inlet-valve H^{17} . The lever H^4 remains in this 45 last position (and the live steam is admitted through the inlet H^{19}) until it comes in contact with its cut-off F , which forces the lever up and closes the inlet H^{17} .

A' indicates a cam similar to cam A , secured 50 upon the disk upon the opposite face thereof and at a point diametrically opposite the cam A . The purpose of this cam is to engage the lever H^3 , which projects over the face of the disk opposite the lever H^4 , and 55 which operates the steam-inlet valve of the cylinder B corresponding to the valve H^{17} , such valve being indicated by L^{14} and connected by suitable levers L^8 , L^9 , L^{10} , L^{12} , and L^{13} with the said lever H^3 .

60 The cut-offs F' and F^3 serve the same function as the cut-offs F and F^2 for operating the levers H^2 and H^3 when they are set to cause a reverse motion of the engine. All of the 65 cut-offs are held to the disk by loose clasps a , that slide under the inner rim of the disk provided for this purpose, as shown in Figs. 2 and 3.

The several cut-offs are actuated by lever mechanisms connecting them with the weights E and E' on both sides, each of such 70 mechanisms comprising a nut or lug E^{15} , which slides in a slot in the angle-lever E^{14} , pivotally mounted in the bracket E^{16} and having its inner end pivotally connected with a link E^{18} . The several links E^{18} connect with the 75 adjacent slide-blocks E and E' , which blocks are connected to the slide-blocks E^4 and E^5 in the manner heretofore described. The blocks E and E' are held against centrifugal force 80 by the springs E^6 and E^7 .

The purpose of providing the weights E^4 and E^5 and connecting them with the slide-blocks E and E' , as shown, is twofold: First, such arrangement serves to balance the disk, and, secondly, it also serves to make the movement of the two weighted blocks E and E' uniform. 85

As before stated, an upright shaft H^6 is connected to a curved lever H and a similar shaft L connected to a corresponding lever H' , which shafts and members H^6 and L are respectively connected with the rock-shafts K and K^3 and K^4 and K' . The shafts K , K^3 , K' , and K^4 are operated by movement of the levers H and H' , and when the rock-shafts K 95 and K^3 are turned they actuate the abutment in the cylinder B , while the shafts K' and K^4 when turned operate the abutment in the cylinder B' .

In operation when the disk D revolves the 100 weights E and E' are thrown out by centrifugal force, and as they are thus moved they will, through the intermediate devices which connect them with the several cut-offs F and F' and F^2 and F^3 , cause such cut-offs to slide toward the center line of the machine, as indicated by dotted lines in Fig. 2. The adjustment of the cut-off F in connection with the cam A serves to cut off the steam when the piston is moving in direct motion from left 110 to right, the cut-off F' serving the same purpose in the reverse motion, as heretofore explained. 105

By referring now more particularly to Figs. 6 and 7, which illustrate the valves, &c., appertaining to the cylinder B' , it will be noticed 115 the inlets H^{19} and H^{20} are connected with the first compartment of the steam-chest and are opened and closed by the valve H^{23} , which operates back and forth in a close 120 steam-tight aperture through the medium of the connecting devices which join it with the rock-shafts R and R' heretofore referred to. The valves H^{17} and H^{18} cover the inlets H^{19} H^{20} in the second compartment of the steam-chest, H^{18} remaining closed while the piston 125 is moved from left to right, while the valve H^{17} during such movement of the piston is alternately opened and closed by the lever and cut-off devices operated in connection therewith until the motion of the piston is reversed, when the valve H^{18} becomes the operating-valve and the valve H^{17} the closure 130 for inlet H^{19} . The port H^{21} serves as the ex-

haust when the piston moves from left to right and H^{22} the exhaust when the piston moves from right to left. The valves H^{35} and H^{36} are operated, respectively, over the 5 ports H^{21} and H^{22} and are connected by parallel crescent frame-sections H^{26} , which slide back and forth in guides, as shown, such valves H^{35} and H^{36} being connected to the said frame H^{26} by the cross-levers H^{27} and 10 H^{28} . When the rock-shafts R and R' are turned to the right, valve H^{35} is moved forward to close opening H^{21} , and the valve H^{36} is also moved forward away from the opening H^{22} , such operation occurring in reverse 15 motion of the piston. When, however, the rock-shafts R and R' are turned in a reverse direction, the port H^{21} is open and port H^{22} closed. The abutment M^6 in the cylinder B is actuated by similar lever devices connect- 20 ing it with the rock-shaft $K^3 K$, which are, however, preferably disposed to the left of the said cylinder, as shown in Fig. 1, and are actuated by reason of the coaction of the cam A , levers H' , L , L' , L^6 , L^2 , L^3 , L^4 , and L^5 . 25 The valves on the cylinder B are operated by the coaction on the under side of cam A' , levers H^8 , L^8 , L^9 , L^{10} , L^{12} , and L^{13} , the exhaust-port valves for the cylinder B being actuated by the rock-shafts R R' and the levers 30 L^{18} , L^{19} , L^{20} , and L^{23} , while the exhaust-port valves in cylinder B' are actuated by levers H^{34} , H^{32} , and H^{31} , connected to the same rock-shafts R and R' . The abutments O^{10} K^{18} , as 35 also the valves connected with the cylinders B^2 B^3 , are formed and actuated precisely as those above described and therefore need not be specifically set out. The disk portions D^2 for operating the several valve devices for the cylinders B^2 B^3 are also formed precisely 40 as the disk portions D for operating the valve mechanisms for cylinders B B' , as are also the cam devices A^2 and levers K^6 and O' , which connect the rock-shafts O^{12} , O^2 , and O^3 with shaft O^{18} , which shaft in turn is connected by the levers O^5 , O^6 , O^7 , and S with the abutment O^{10} . In the same manner and with similar lever devices abutment K^{18} , cam A^3 , and connecting levers are furnished and actuated. The valves of cylinder B^2 are actuated 45 by under side of cam A^2 and levers r , r' , and r^3 , while the valves of cylinder B^3 are actuated by the under side of cam A^3 and levers n , n' , n^3 , n^4 , n^5 , and n^6 , the exhaust-ports being also operated in a manner similar to the 50 exhaust-port referred to, it being understood that the arrangement of the several devices for actuating the valves and abutments on the cylinders B^2 and B^3 are arranged at right angles to those for operating the lever members for cylinders B and B' , so that the engine-shaft will receive a live-steam impact force at every quarter-revolution of the same, as in my other patent referred to.

From the foregoing description, taken in 60 connection with the accompanying drawings, the complete operation of the invention is best explained as follows: Assuming the parts

to be in the position shown in Figs. 1 and 2, it will be noticed that when the engine is set to run from left to right the steam will enter 70 into the outer compartment of the steam-chest through the valve-opening H^{17} and from there through the inlet H^{19} . Live steam entering within cylinder between the abutment and piston forces the piston and shaft, together with the actuating-disk, in the direction indicated by the arrow, the cam A in its movement engaging with the inturned end of the lever H^4 and drawing it down to open the valve H^{17} , while the cut-off F' engages the 80 lever H^4 and moves the valve H^{17} to its closed position to cut off steam-supply, it being understood that such valve will remain closed until the cam A again comes around and pulls the lever H^4 down. As the disk D is 85 thus operated with the shaft the cam A will raise the lever H , and through the lift-shaft H^6 it will rock the shafts K' and K^4 , and thereby at the proper time lift the abutment M out of the path of the piston within the cylinder B' , 90 it being understood that during this operation the valve and cut-off devices in the cylinders B , B^2 , and B^3 are operated in a like successive but alternate manner by means of lever devices corresponding with the levers 95 H and H^6 and suitable connections with the rock-shafts, which connect with the respective abutments of the said cylinders B , B^2 , and B^3 . It will thus be seen I have provided means for positively and automatically shifting 100 the several valves for intermittently supplying live steam to the cylinders and for almost instantly effecting a reverse action of the engine. It will be also clear that while the piston is receiving its impact force from 105 live steam the pistons within the other cylinders are having the full effect of the partially-expanded or exhausting steam force.

While I have in this case shown four chambers arranged so that the shaft will receive a 110 live impact force at each half of its revolution, it is manifest a less or greater number of such cylinders and operating devices may be employed. If less, the cam-disks are provided with a less number of cut-off devices, 115 and if more than four cylinders are used such disks are provided with a proportionately increased number of such cut-offs.

By providing cut-off devices having centrifugally-operated means for shifting them 120 to or from the fixed cams on the disks such devices will act as governor means for regulating the speed of the engine. Thus should the engine be running at a very rapid speed the cut-offs will be rotated forward on the 125 disk toward the fixed cams and in consequence provide for a quick lift action of the levers H^4 and H^5 and the others corresponding thereto, and thereby produce a quick cut-off of the live steam, it being obvious that as 130 the force of live steam is thus decreased the spring E^7 and E^6 , through the medium of the slide-blocks E and E' , will serve to increase the space between the cams on the disk and

the cut-offs, and thereby provide for an increased live-steam supply. It will thus be seen a direct combined cut-off and governor mechanism is provided which, owing to its 5 peculiar construction, will positively and effectually serve for its intended purpose.

Having thus described my invention, what I claim, and desire to secure by Letters Patent, is—

- 10 1. In a rotary engine of the character described; the combination with the sliding abutment; the steam-chest, and the throttled valve operating therein; of a disk rotatable with the drive-axle; abutment-shifting-lever devices; cams fixedly held on the rotatable disk for operating such abutment-lever devices to lift the abutment; the throttled-valve-shifting devices and the centrifugally-operated automatically-adjustable cams arranged on the rotatable disk for shifting the throttled-valve-operating devices, all being arranged substantially as shown and for the purposes described.

- 20 2. A rotary engine, comprising a fixed annular chamber, a sliding abutment therefor, a drive-shaft having a concentric piston, a steam inlet and exhaust, arranged at each side of the abutment, opening into the chamber, a shifting valve mechanism for simultaneously closing the steam-inlet at one side, an exhaust at the other side, and opening the alternate inlet and exhausts, and a supplemental cut-off valve, operated over the steam-inlet, and mechanism operated from the drive-shaft for imparting a reciprocating action to the said supplemental cut-off valve.

- 30 3. A rotary engine, comprising a fixed annular chamber, a sliding abutment, the drive-shaft having a concentric piston, shaft-operated means for lifting the abutment, a steam-chest for the chamber having a duplex set of steam-ports, one set being at each side of the abutment, a hand-operated sliding valve for opening and closing the inlet of one set and the exhaust of the other set of ports, said chest having independently and automatically operated supplemental valves movable over the inlets and ports; fixed cams carried by the shaft to move the said supplemental valves in one direction, centrifugal adjustable cut-offs for moving them to their reverse direction, and means for setting either of such supplemental valves out of engagement with the shaft, cam and cut-off devices, for holding such valve to close off its respective steam-inlets, as specified.

- 40 4. The combination with the fixed cylinder, having an annular steam-chamber provided with a sliding abutment; the drive-shaft having a concentric piston and a fixed disk, said disk having means for raising the sliding abutment; a steam-chest having an inlet-port and exhaust-port opening into the steam-chamber at each side of the abutment; a hand-operated slide-valve for opening and closing the steam-inlet, at one side of the abutment, and the exhaust at the other side

of such abutment; independently-operated slide-valves movable over the steam-inlets, operating mechanism for such valves, such 70 mechanisms including a lever adapted to be projected in the path of the fixed disk, means for simultaneously setting such operating mechanism to alternately bring one of said levers in an operative position as the other is moved out of line with its adjusting devices, and means mounted on the fixed disk for imparting an alternate opening and closing movement on the said lever as specified.

5. A rotary engine, comprising a plurality 80 of fixed annular chambers, a drive-shaft having a series of concentric pistons projected in diametrically opposite directions, said pistons fitting to travel one in each steam-chamber, each chamber having a sliding abutment, such abutments projecting radially from the chamber in the same alinement; a cam mechanism on the shaft, having means for alternately lifting the abutments at predetermined intervals; an exhaust and inlet 90 port at each side of the abutment-shaft, of the cylinder slide-valves for alternately opening and closing the inlet at one side and the exhaust at the other side of the abutment; supplemental valves operating over the inlet-ports, said valves having operating means adapted to engage and be set to alternate positions by the cam-disk, means for simultaneously setting both valve-operating means, one set of valve-operating means to the position to be engaged by the operating-cam, and the other set of operating means to be set in position out of engagement with the aforesaid operating-cam, all being arranged, substantially as shown and described. 105

6. In a rotary engine, substantially as described, the combination with the annular chamber; the drive-shaft; the steam inlets and exhaust; of the reciprocating inlet-valve, a rock-lever connected to and adapted to impart a shifting motion thereto; a disk secured on the shaft, having a fixed cam for engaging and moving the said rock-levers in one direction, and a cam automatically adjustable by centrifugal action for engaging and moving the said lever to its reverse position as specified. 110

7. In a rotary engine as described, the combination, with the annular steam-chamber, the sliding abutment, the steam-chest having a duplicate set of inlet and exhaust ports, the adjustable valve devices H²³, the supplemental valves for the steam-inlets, and the pivotal levers for operating such valves; of the drive-shaft having the concentric piston; 120 the disk D fixedly held on such shaft, the cams A and A' fixedly secured to the disk, the pivotal cut-offs F and F', the sliding blocks E and E', the springs E⁷ and E⁶, the slide-block E⁴ E⁵ and the lever connections 125 joining the blocks E⁴, E⁵ E' and F', all being arranged substantially as shown and for the purposes described. 130

8. The combination of the cylinders B and

B', each having an annular chamber, the drive-shaft having oppositely-disposed concentric pistons, such chambers having steam-chests, each provided with an inlet and exhaust port at each side of the abutment; the slide-valves H²³, the rock-shafts R and R', having cranks connected with the slide-valves H²³, the slide-frames movable with the valves H²³, having exhaust-port-covering members, the supplemental cut-off valves, the levers H⁴, H⁵, H² and H³, connected thereto, the levers H and H', abutments M and M⁶, the shafts H⁶ and L, connected to the levers H and H', the rock-shafts K, K', K³ and K⁴, having lift-rods connected with the abutments, and crank members, the rods H⁸, L², L' and H⁷, connecting the crank members and the shafts H⁶ and L, and the disk D having fixed cams A and A' and adjustable cut-offs F, F', F² and F³, all being arranged substantially as shown and described.

9. In a rotary engine, the combination with the cylinder, the sliding abutment, the shaft having a concentric piston; the steam-chest for the cylinder having inlet and exhaust port opening to the cylinder at each side of the abutment; independently and alternately operating valves for the inlets to the steam-chests; mechanism operated by the shaft for automatically operating the said independent and alternate operating valves and for lifting the abutment; and a supplemental shifting valve mechanism for alternately opening and closing the inlet and exhaust ports to the cylinder, all being arranged substantially as shown and described.

JAMES C. WALKER.
